UNITED STATES PATENT OFFICE.

CHARLES K. TETER, OF CLEVELAND, OHIO, ASSIGNOR TO THE TETER MANUFACTURING COMPANY, OF CLEVELAND, OHIO, A CORPORATION OF OHIO.

ETHER-ADMINISTERING APPLIANCE.

1,362,201.

Specification of Letters Patent. Patented Dec. 14, 1920.

Application filed December 13, 1912. Serial No. 736,632.

To all whom it may concern:

Be it known that I, CHARLES K. TETER, a citizen of the United States of America, residing at Cleveland, in the county of Cuyahoga and State of Ohio, have invented certain new and useful Improvements in Ether-Administering Appliances, of which the following is a specification.

My invention relates to improvements in ether administering appliances, and more particularly to such an appliance which is adapted to be used in association with apparatus for administering gaseous anesthetics or mixtures of such gases, whereby definite controllable percentages may be given by the operative. The object of my invention is to provide means for accurately controlling the proportion and rate of administration of the different anesthetics, with the least attention possible on the part of the operative.

In my Patent No. 883,987, granted Apr. 7th, 1908, I have shown means for accomplishing the same general results now sought to be attained, but the apparatus therein shown requires a considerable degree of technical skill, and close attention on the part of the operative, at all times during the administration of the anesthetics. I may briefly refer to the apparatus shown and described therein, by stating that it consists of suitable means for administering two such gases as oxygen and nitrous-oxid in suitable proportions, with which is mixed ether vapors for inducing deeper anesthesia. The different proportions of the gaseous and vaporized reagents, are controlled by a series of successively operated valves, as fully explained in said patent.

The apparatus of my invention relieves the operative of numerous adjustments, and insures the administration of known indicated percentages of the anesthetics, while permitting said operative to give his closest attention to the condition of the patient.

The structural features of my improvement may best be explained, by making reference to the accompanying drawings, wherein:—

Figure I, is a plan view of the controlling and mixing apparatus for the gases, associated with a vapor warmer and ether administering appliance, pursuant to the principles of my present invention.

Fig. II, is an enlarged side elevation of

the ether attachment with the containing jar broken away.

Fig. III is a horizontal sectional view through the valve-mechanism thereof.

Fig. IV, is a plan view of the gearing for controlling the different valves.

Fig. V, is a vertical sectional view on line V—V of Fig. III.

Fig. VI, is a vertical sectional view at right angles to the former, on line VI—VI of Fig. III.

Fig. VII, is an enlarged detail of a modified form of valve-adjusting and operating mechanism, and

Fig. VIII, is a detail thereof, showing the operating gear.

Throughout the different figures of the drawings, I have employed the same character of reference to indicate similar parts.

By referring to my above mentioned patent, identification of the different components of my improved apparatus will be greatly facilitated. Fig. I of the present drawings illustrates two sets of flasks *a a*, *b b*, respectively containing oxygen and nitrous-oxid under high pressure. These are removably mounted upon the mixing head *c'*, and the flow of gases therein is governed by the controlling and reducing valves *c*, *d*, and *c' d'*. Accordingly, they will be supplied to the mixing chamber *e* in the desired proportion, from which they pass through the vapor warmer *f*, and administering appliance *g*, to the ducts *g' g''* or either of them, which are respectively connected with the nasal-inhaler and mouth tube, (not shown), whereby the anesthetics are directly administered to the patient.

An ether jar *g²* (shown as broken away), is screwed below the valve mechanism, which governs the flow of gaseous reagents, and permits their admixture with the ether vapors in the percentages required. Accordingly, the adjacent vapor-warmer *f*, for safety, may be electrically heated. The cap of the ether jar comprises a multi-chambered member, whose passages are controlled by three separate valves, also governing the circulation through the ether jar and the exits to the administering apparatus for the patient. Fig. III, best shows the chambered casing *h*, wherein the conical, rotatable valves *i*, *i'* and *i''* are seated. Chamber *h'* connected with the vapor-warmer, communicates with chamber *h''*

through the valve-port i^2 ; said chamber h'' extending beneath valve i'' as best shown in Fig. V, which valve being entirely open from below, normally permits the flow of 5 gas directly to the ducts $g' g''$, and with the adjustment shown, no admixture of ether vapor is obtained. Accordingly, nitrous-oxid and oxygen are administered in the proportions regulated by the mixing 10 valves.

Valve i communicates directly with the ether jar, through the open bottomed port i^3 , while valve i' , is open-bottomed, and communicates with chamber h^3 through its port 15 i^4 , when rotated into alignment with the communicating opening in the casing. Chambers h'' and h^3 merge or communicate beneath valve i'' , which is open-bottomed in order to permit the flow of gas from either 20 or both of said chambers, and direct it to the appropriate duct or ducts. From this general explanation, it will be understood that all gases flowing through chamber h'' will remain unmixed with the ether vapors, 25 while all gases flowing through chamber h^3 , must first pass through the ether jar, and accordingly the proportionate flow of the gases through these two chambers, will govern the percentage of ether administered.

With these general features in mind, I 30 may now explain the manner in which the valves are concurrently or separately controlled, for the purpose of administering anesthetics, in accordance with the varying 35 needs of the patient.

The thumb-nut k is connected by stem k' and its gear k'' with the meshing gear 1, controlling valve i'' . Thus the thumb-nut is rotatable for the purpose of independently 40 controlling the flow of gases through the ducts $g' g''$. A stationary pointer or indicator m is provided for the purpose of designating the position in which the valve i'' is disposed, whereby either the duct g' 45 or g'' may be supplied with gas or entirely cut off therefrom, or both may receive an equal supply. The sleeve n is provided with a larger indicator or pointer n' and a handle n'' , whereby the sleeve and its connected gears and valves may be rotated. The graduated scale n^2 upon the top of the casing is calibrated to show the percentage of ether administered in the various positions of said pointer and connected valves. 55 The sleeve n is provided with the gear o'' turning independently of the stem k' ; said gear meshing with the valve gears $o' o'$, which in turn respectively control the position of the valves i and i' . Thus the said 60 valves may be rotated in unison and in the same direction, for the purpose of controlling the flow of gases through the ether jar.

Inasmuch as ether is highly volatile, it is 65 desirable that the valves shall be held in

sealed relation within their conical seats. Accordingly, each valve stem is provided with a set screw p , bearing vertically thereon, through an intermediate washer p' , and a lock-nut p'' is provided for each 70 screw, as is well shown in Fig. VI. The separable gearing for each of the valves is shown in assembled relation in Fig. IV.

In order to secure certain independence of movement between the valves and gears, 75 although permitting their accurate actuation as before, I may interpose a spring between the valve stem q and the set screw p , as shown in Fig. VII, whereby the valve is resiliently held within its conical seat. 80 The actuating gear wheel, as l , is provided with a radial slot o^3 , into which extends the pin s , provided upon the valve part i'' . Thus the valve part will be closely and accurately seated within its conical recess, 85 and although controllable by its actuating gear, these parts do not require the same exactness in construction or mounting, because of the accommodation provided for in the slotted connection between the parts. 90 It will be understood that the other rotatable valves may be similarly provided with the spring adjustment, and slotted actuating gear, just described.

The apparatus being assembled as shown 95 and described, the desired current of nitrous-oxid and oxygen, mixed in the proportions required, is first insured by opening and adjusting the valves $c d, c' d'$. The vapor warmer, of any approved type, is also 100 placed in operation, and with the valve parts rotated to the positions indicated in Fig. 3, this anesthetizing mixture will be available through both of ducts $g' g''$, unmixed with ether. The rotation of the 105 thumb-nut k will direct the flow through one or the other of these ducts, as required; the position of the valve being shown by the indicator, and the initial flow of gases being shown by the arrows. Assuming that five 110 per cent. of ether is desired, handle n'' is rotated to sweep its indicator over five divisions of the graduated scale, thereby turning valves $i i'$ in a counter-clockwise direction partially to open the respective 115 ports i^3 and i^4 . Although the volume of the nitrous-oxid mixture will still flow through the port i^2 and chamber h'' , part of said mixture will be directed down through the ether jar, and up through valve i' , as indicated by the arrow in Fig. VI. From thence, this portion of the ether charged reagent will flow through chamber h^3 , and valve i'' to the connected duct or ducts leading to the inhaler apparatus. Obviously, 120 by rotating the handle n'' still farther, and with it the valves $i i'$, still larger percentages of ether may be administered until the maximum charged mixture is obtained, when ports i^3 and i^4 respectively register 125 130

with the openings to chamber h' and h'' . Under these conditions all of the nitrous-oxid mixture is directed through the ether jar, and under conditions of normal flow, 5 approximately twenty per cent. of ether will be administered to the patient. The vapor warmer, through which the gases pass, serves to raise the temperature of the normally chilled nitrous-oxid, so that it is 10 capable of taking up a relatively large proportion of the ether vapors.

In the event that ether alone is to be administered, the controlling valves c c' may be closed, and an air valve t , opening 15 into the mixing chamber, is thrown open for permitting the patient to breathe warm air mixed with the ether vapors, directly through the gas-supply line. Of course, the oxygen remains always available by means 20 of its independently actuated valves, for the purpose of reviving or stimulating the patient, whenever the need arises. It will be understood that the vapor warmer is utilized to afford a supply of gas or gaseous-medium 25 at the desired temperature, whereby the administration of ether vapors may be definitely gaged, irrespective of the initial temperature of the gas or gases, or of the anesthetizing-room. In addition, the inter- 30 connected valves permit the gases to be directed through the ether jar in varying regulated proportions, so that such varying proportions of said gas or gases may become saturated with the ether vapors, and there- 35 by permit the accurate control of administration of that anesthetic.

From a consideration of the foregoing, it will be readily appreciated how simply the anesthetization of the patient may be effected and controlled. The operative employing my improved apparatus is required 40 to adjust merely two regulating parts, viz., the thumb-nut k and the handle n'' in order to effect absolute control of the anesthetizing 45 reagents, as above described. This simplicity of automatic operation for the various valve ports is peculiarly important in view of the frequent emergencies arising during the administration of anesthetics. 50 Thus, if complete or continued relaxation of the patient is not obtainable with the heated nitrous oxid mixture, the ether supply in any desired percentage is at once available for superinducing complete an- 55esthesia, merely by rotating the indicator to the proper position. Moreover, the associated nasal-inhaler and the mouth tube may alternatively be employed, or both may be brought into service at once, the instant 60 they may be required.

Although I have shown separate means for heating the gases supplied to the ether jar, other means than the connected vapor warmer obviously may be employed for se- 65 curing the desired volatilization of this

anesthetic. Again, certain specific features of valve construction and connecting mechanism therefor, have been explicitly described above, but my invention is not necessarily restricted thereto, and accordingly, I 70 claim as new and desire to secure by Letters Patent, the following:—

1. In apparatus for administering known percentages of ether and a gaseous anesthetic, the combination with controllable 75 means for supplying a definite current of such gaseous anesthetic, of a warming device, an ether receptacle, an adjustable controlling appliance associated therewith, adapted to divert known volumes through 80 said ether appliance, and an indicator for designating the percentage of ether administered under different conditions of adjustment, substantially as set forth.

2. In apparatus for administering known 85 percentages of ether and a gaseous anesthetic, the combination with controllable means for supplying a constant current of such gaseous anesthetic, of a warming device, an ether receptacle, an adjustable controlling appliance associated therewith, comprising a plurality of valves governing the 90 flow of said gaseous anesthetic to the ether receptacle, and to the administering apparatus, interconnecting operating mechanism 95 for said valves, and an indicator associated therewith for designating the percentage of ether being administered, substantially as set forth.

3. In apparatus of the class described, the 100 combination with controllable means for supplying a current of suitable gaseous anesthetic, of a safety warming device for such anesthetic, an ether receptacle, an adjustable controlling appliance associated 105 therewith, comprising a plurality of valves governing the flow of said gaseous anesthetic to the ether receptacle, and to the administering apparatus, interconnecting operating mechanism for said valves, and 110 an indicator associated therewith for designating the percentage of ether being administered, substantially as set forth.

4. In apparatus for administering known 115 percentages of a volatile anesthetic mixed with a gaseous anesthetic, the combination with controllable means for supplying a current of such gaseous anesthetic, of a receptacle for the volatile anesthetic, a safety warming appliance, an adjustable control- 120 ling mechanism for regulating the flow of the gaseous and volatile anesthetics to administering apparatus, and an associated indicator adapted to designate the proportionate mixture of said anesthetics, substantially 125 as set forth.

5. In a controlling apparatus for volatile liquids, the combination with a receptacle for such liquid, of an associated valve mechanism comprising two interconnected valves 130

controlling the access to said receptacle, an additional valve controlling the exit from said receptacle, and indicating devices respectively associated with said valves, substantially as set forth.

6. In apparatus of the class described, the combination with an ether jar of a closure-member therefor, associated regulating-mechanism comprising two interconnected 10 rotatable valves governing the access to said receptacle, means for supplying a gaseous-medium to said ether jar at an elevated temperature, and an indicator adapted to designate the position of the valves, substantially 15 as set forth.

7. In apparatus of the class described, the combination with a container for a vaporizing anesthetic maintained at substantially normal temperatures, of a gas supply line, 20 an indicator device associated therewith, a coöordinated valve mechanism governing said container, adapted entirely to cut off or to administer through the gas supply, varying positively indicated proportions of the 25 anesthetic, and means for heating the gas supply substantially to increase the saturation, substantially as set forth.

8. In apparatus for administering mixtures of anesthetizing reagents, the combination 30 with separate supplies of gaseous and vaporous reagents, of a heating device for maintaining the gaseous reagent at an elevated temperature, associated valve mechanism adapted alternatively to secure the admistration of the gaseous or vaporous reagent alone, or both in predetermined mixture, a percentage indicator provided upon the valve mechanism, and an adjustable air valve connected to permit the entrance of 40 air to the heating device, substantially as set forth.

9. In apparatus of the class described, the combination with an ether jar approximately at normal or atmospheric temperature, of 45 means for supplying a gas thereto at a temperature materially higher than that of said ether jar, and controlling valve-mechanism comprising connected adjustable valve parts adapted to pass the gas in definite varying 50 proportions above and directly through the ether jar, and indicating mechanism associated therewith, whereby definite known percentages of ether may be administered, substantially as set forth.

55 10. In apparatus of the class described, the combination with an ether jar, of a gas supply line, and means for maintaining the gas at an elevated temperature, and valve mechanism associated with the ether jar, 60 comprising inter-connected valves respectively controlling the direct flow of gas and the complementary flow of gas through the ether jar, a percentage indicator, and actuating means for said inter-connected valves, 65 substantially as set forth.

11. Apparatus for administering vapor having therein a delivery tube, a vaporizing chamber adapted to contain a volatile liquid, and passages for dividing and for delivering a current of gas containing oxygen respectively to said delivery tube directly and to said vaporizing chamber and thence to said delivery tube, in combination with means for opening one and closing another of such respective passages simultaneously to the same extent, whereby a predetermined portion of said current may be saturated with vapor of the volatile liquid and delivered with the remainder of said current, the total volume of said current remaining constant at a given pressure.

12. Apparatus for administering vapor having therein gas ingress means, vapor delivery means and means for causing a current of gas containing oxygen to pass therethrough, in combination with a vaporizing chamber and means having therein a plurality of passages whose apertures are simultaneously and oppositely adjustable to cause a constant volume of the gas flowing from 90 said ingress means to said delivery means to be diverted from, to enter, or to be partly diverted from and partly to enter said vaporizing chamber.

13. Apparatus for administering vapor, having therein a delivery tube, a vaporizing chamber adapted to contain a volatile liquid, and means for supplying at a fixed maximum pressure, for dividing and for delivering a gaseous current of constant volume at 100 a given pressure in variable predetermined proportions respectively to said delivery tube directly, and to said vaporizing chamber and thence to said delivery tube, substantially as set forth.

14. Apparatus for administering vapor, having therein ingress means, vapor delivery means and means for causing the flow of a gaseous current therethrough, in combination with a vaporizing chamber and means 110 having therein a plurality of passages whose apertures are simultaneously and oppositely adjustable to cause a constant volume of the gas flowing from said ingress means to said delivery means to be diverted from, to enter, or to be partly diverted from and partly to enter said vaporizing chamber, substantially as set forth.

15. Apparatus for administering vapor, having therein ingress means, vapor delivery 120 means and means for causing the flow of a gaseous current therethrough, in combination with a vaporizing chamber and means having therein a plurality of passages whose apertures are simultaneously and oppositely 125 adjustable to cause a constant volume of the gas flowing from said ingress means to said delivery means to be diverted from, to enter, or to be partly diverted from and partly to enter said vaporizing chamber, and an indi- 130

cating device associated with the gas controlling means for showing the ratio of vapor, substantially as set forth.

16. Apparatus for administering vapor, 5 having therein a delivery tube, a vaporizing chamber adapted to contain a volatile liquid, and passages for dividing and for delivering a gaseous current respectively to said delivery tube directly and to said vaporizing 10 chamber and thence to said delivery tube, in combination with means for opening one and closing another of such respective passages simultaneously to the same extent,

whereby a predetermined portion of said gaseous current may be saturated with vapor 15 of the volatile liquid and delivered with the remainder of said current, the total volume of said current remaining constant at a given pressure, substantially as set forth.

In testimony whereof I do now affix my 20 signature in the presence of two witnesses.

CHARLES K. TETER.
